UNITED STATES PATENT OFFICE.

ANTHONY J. HAMMAN, OF BALTIMORE, MARYLAND, ASSIGNOR OF ONE-HALF TO F. HENKELMAN, OF SAME PLACE.

DESIGN FOR A PUZZLE-BOX.

SPECIFICATION forming part of Design No. 28,299, dated February 15, 1898.

Application filed January 6, 1898. Serial No. 665,866. Term of patent 7 years.

To all whom it may concern:

Be it known that I, ANTHONY J. HAMMAN, a citizen of the United States, residing at Baltimore, in the State of Maryland, have invented a new and original Design for a Puzzle-Box, of which the following is a specification.

This invention relates to a new and original design for a puzzle-box; and it has for its object to provide a design of this character that shall be both useful and ornamental.

The leading feature of the design resides in a rectangular box having a group of triangular blocks arranged in the form of a Maltese cross, with their adjacent inclined sides disposed in parallel planes and their straight outer sides spaced from and parallel with the sides of the box, a pair of straight diagonally-crossed strips intersecting each other at the center of the box and lying within the diagonal spaces between said blocks, and separate isolated straight strips arranged in line with and beyond the ends of the crossed strips within the outer portions of said diagonal spaces.

In the drawings, Figure 1 is a plan view of a puzzle-box embodying the herein-described design. Fig. 2 is a transverse sectional view on the line 2 2 of Fig. 1. Fig. 3 is a sectional view on the line 3 3 of Fig. 1.

Referring to the accompanying drawings, the numeral 1 designates a rectangular box, within which is arranged a rectangular group of triangular blocks 2. The triangular blocks 2 are grouped in the form of a Maltese cross, with their inclined sides disposed in parallel planes and their straight outer sides spaced from and parallel with the straight sides of the box. A pair of straight diagonally-crossed strips 3 are arranged within the box between the upper and lower sides thereof and intersect each other at the center of the box, said strips extending from the center of the box into the diagonal spaces between the triangular blocks 2. The design is completed by the isolated strips 4, which are arranged in line with and beyond the ends of the crossed strips 3 and which are disposed within the outer portions of said diagonal spaces.

What is claimed is—

The design for a puzzle-box herein shown and described.

In testimony that I claim the foregoing as my own I have hereto affixed my signature in the presence of two witnesses.

ANTHONY J. HAMMAN.
